UNITED STATES PATENT OFFICE.

JOHAN HJALMAR CARLSTEDT, OF GEFLE, SWEDEN.

GRAVITY-LOCK.

1,028,860.

Specification of Letters Patent. Patented June 11, 1912.

Application filed April 15, 1911. Serial No. 621,397.

To all whom it may concern:

Be it known that I, JOHAN HJALMAR CARLSTEDT, a subject of the King of Sweden, residing at Gefle, in the Kingdom of Sweden, have invented new and useful Improvements in Gravity-Locks, of which the following is a specification, reference being had to the drawings accompanying and forming a part hereof.

10 This invention relates to improvements in springless or gravity locks for doors and the like.

The object of the invention is to provide, a lock of this character which has only a 15 small number of parts of a simple form and which is therefore comparatively easy and inexpensive to manufacture and in which the parts may be made of such dimensions as to be strong without the lock as a whole 20 being bulky.

The invention consists, chiefly, in this that the lock casing is movable up and down and acts by its own weight and the weight of the parts inclosed in the same directly on 25 the latch bolt or a bolt-actuating member or members connected thereto in such a manner as to cause the said bolt to advance by the descending movement of the casing.

The invention further comprises the construction and combination of parts herein-after set forth.

In the drawing, I have shown by way of example a door lock embodying the invention.

35 Figure 1 is a side view of the lock with the face of cover plate partly broken away to show the operating parts, said parts being shown in their advanced or locking position which they normally take up, whether the 40 door be open or closed, except at such times as they are retracted by the manipulation of the door knob or handle. Fig. 2 is a similar view of the lock with the parts in retracted positions. Fig. 3 is a vertical 45 cross-section of the lock. Fig. 4 is a horizontal section of the same. Fig. 5 is a front view of the latch bolt, and Fig. 6 is a front view of the striker plate with the hole for the said latch bolt.

50 Referring to the drawing, 1 is the lock casing set in a recess in the edge of the door. The said recess is somewhat higher than the casing so as to allow the latter to move vertically therein. The casing is 55 guided in its movement by two or more vertical bars 2 or the like engaging correspond-

ing grooves in the outer sides of the side walls of the casing and bearing with their outer sides on the walls of the recess in the edge of the door. The width of the casing 60 is somewhat less than that of the recess, *i. e.* the bars 2 project somewhat outside the sides of the casing, as shown in Fig. 3, by which the casing is held in proper position 65 out of contact with the walls of the recess and guided during its vertical movement.

Journaled in the lower part of the rods 2, below the casing 1, is the spindle or shank 3 of the door knob or handle. Attached to the said spindle, which is preferably rectangular in shape, is a lift arm 4. This arm normally takes up the horizontal position shown in Fig. 1 and serves to support and raise the casing and to be actuated by the same for the advancement of the latch bolt. 70 Attached to the spindle 3, at right angles to the arm 4, is a second arm 5 entering a recess or opening in the rear part of the latch bolt 6 and serving as a bolt-actuating member. The shank of the bolt 6 is guided at 75 its sides by one side wall of the casing and the arm 5 and at its lower side by a plate 7 or the like. The upper half of the head of the bolt is obliquely cut, as shown in Figs. 80 4 and 5 so as to cause the said bolt to slide inward by the lateral pressure thereon exerted by the door jamb or striker plate, when the door is forcibly swung into closing position. In order to prevent the bolt from 85 sliding inward so as to unlock the door when the latter is exposed to pressure, the lower half of the head of the bolt is partly cut away, as shown in Figs. 2 and 5 leaving a comparatively thin plate of uniform thickness adapted to enter a corresponding 90 downward extension of the bolt opening in the striker plate 8 (Fig. 6). The opening in the said plate must obviously be sufficiently high to allow the bolt head to move vertically therein when the door is locked 95 or unlocked.

Placed above the latch bolt 6 is a locking dog or tumbler 9 adapted to swing about a pivot pin 10 and to drop into a notch 11 in the bolt 6 when the latter is moved sufficiently toward the right from the position shown in Fig. 1.

The described lock works as follows: When the lock is to be opened, the shank 110 or spindle 3 is turned in a direction causing the arm 4 to swing upward and the arm 5 to swing laterally from the position shown

in Fig. 1 into the position shown in Fig. 2. In so doing, the casing 1 is raised by the arm 4, and the bolt 6 is moved inward by the arm 6. If the lock is thereupon released, 5 the casing 1 and the bolt 6 act by gravity to press the arm 4 downward, thereby turning the spindle 3 and causing the arm 5 to advance the bolt 6. If the door handle is operated so as to turn the arms 4 and 5 from the position shown in Fig. 1 toward the right (*i. e.* in the clockwise direction), the bolt 6 is advanced farther into the recess in the door jamb so as to allow the tumbler 9 to drop by gravity into the notch 11 in the 10 latch bolt, thereby securing the latter in its advanced position so that it cannot be retracted, without the tumbler being first raised by a suitable key. The bolt 6 thus serves as a combined latch and locking bolt 15 by which the door may be secured in its closed position.

I claim:

1. In a gravity lock, the combination of a vertically movable casing, a sliding bolt 25 mounted in the said casing, and connections between the said casing and the said sliding bolt causing the latter to be advanced by the descending movement of the casing.
2. In a lock, the combination of a vertically movable casing, a sliding bolt mounted 30 in the said casing, a spindle, bolt-actuating means attached to the said spindle, said means comprising two arms one of which serves as a lift arm for the casing, while 35 the other engages the sliding bolt, causing the same to be advanced by the descending movement of the casing.
3. In a lock, the combination of a vertically movable casing, guide bars engaging 40 corresponding grooves in the said casing, and a sliding bolt mounted in the said casing in such a manner as to be advanced by the descending movement of the same.
4. In a lock, the combination of a vertically 45 movable casing, guide bars engaging

corresponding grooves in the said casing, a sliding bolt mounted in the said casing, and connections between the said casing and the said sliding bolt causing the latter to be advanced by the descending movement of 50 the casing.

5. In a lock, the combination of a vertically movable casing, a sliding bolt comprising a shank and a head mounted in the said casing in such a manner as to be advanced 55 by the descending movement thereof, and a striker plate having an opening for the head of the said bolt, said bolt having the upper part of the head obliquely cut at the end and the lower part thereof partly cut 60 away, leaving a comparatively thin plate of uniform thickness adapted to enter a corresponding downward extension of the opening in the striker plate.

6. In a lock, the combination of a vertically 65 movable casing, a sliding bolt comprising a shank and a head mounted in the said casing, connections between the said casing and the said sliding bolt causing the latter to be advanced by the descending 70 movement of the casing, and a striker plate having an opening for the head of the said bolt, said bolt having the upper part of the head obliquely cut at the end and the lower part thereof partly cut away, leaving a com- 75 paratively thin plate of uniform thickness adapted to enter a corresponding downward extension of the opening in the striker plate.

7. In a gravity lock, the combination of a vertically 80 movable casing, a sliding bolt mounted in the said casing, connections between the said casing and the said sliding bolt causing the latter to be advanced by the descending movement of the casing, and a tumbler for securing the bolt in protracted 85 position when the latter is further advanced.

JOHAN HJALMAR CARLSTEDT.
